DETACHABLE AND COLLAPSIBLE
LAVATORY SEAT

James H. Brown, Pittsfield, Mass.

Application May 31, 1933, Serial No. 673,716

2 Claims. (Cl. 4—239)

The primary object of my invention is to provide a lavatory seat, preferably for the use of children, that may be adjusted to attach to the ordinary lavatory seat and held thereby in a firmly fixed position.

Another object of my invention is to provide a lavatory seat that is collapsible and adapted to fold into a small space for the purpose of shipping or storing.

10 The invention also consists in certain other features of construction and in combination and arrangement of the several parts, to be herein-after specifically described, illustrated in the accompanying drawing and set forth in the appended claims.

15 Referring to the drawing, in which like numerals of reference designate like parts in the several figures:

Figure 1 is a plan view.

20 Figure 2 is a side view.

Figure 3 is a front view.

25 Figure 4 is an end view of the cross arm locking device.

Figure 5 is a side view of Figure 4.

30 Figure 6 is a part sectional view of the back rest locking device.

Figure 7 is a part sectional side view of Figure 6, taken on the line 2—2.

35 Figure 8 is a view of the device in a collapsible position.

Referring to the drawing, 1 represents a dotted outline of an ordinary lavatory seat cover, and the numeral 2 represents a lavatory seat with the hole or opening 3 therethrough. Longitudinal arms 4 are attached to the seat 2 by means of upright hinges 5 and the hinge brace 8. The longitudinal arms 4 are secured to the upright hinge 5 by means of the screws 6, and the upright hinge 5 secured to the hinge brace 8 by means of rivets 9, and the hinge brace to the seat 2 by means of the screws 10. The upright hinge 5 is designed and adapted to operate inwardly. A cross arm 11 extends transversely across the longitudinal arms 4 and is fastened thereto by means of the locking device 13, which is attached to the cross arm 11 by means of a projecting screw 15. The longitudinal arms 4 are provided with metal ferrules 12, which extend therethrough, for the purpose of receiving the locking device 13. The locking device 13 consists of a U shaped member with projecting shoulders on the lower end. A spring 14 is attached to the parallel sides of the locked device 13 and this spring causes the parallel sides of the

locking device to expand after being inserted through the ferrules 12 and causes the projecting shoulders of the locking device to come in contact with the ferrules and prevent it from being pulled therethrough until the spring 14 is compressed. 5 By using a locking device of this nature it will be impossible to remove the cross arm 11 unless the locking devices on both sides of the cross arm are compressed at the same time.

The seat 2 is provided with a back rest 16 that 10 is pivotally attached to the seat by means of the U shaped seat brace 18 and the screws 19. Extending from the U shaped seat brace, and forming a part thereof, is a cover hook 23 which is covered with a pliable material 24 so as not to 15 mar the lavatory seat cover. This U shaped seat brace is provided with slots 21 so that the seat 2 may be adjusted to various sizes of lavatory seats, and is also used for the purpose of providing means for collapsing the back rest 16. The forward end of the seat 2 is also provided with cover hooks, slotted as indicated by the numeral 34 for adjustment, and secured to the seat 2 by means of the screws 32. These cover hooks are also covered with some pliable material 33 so as not to 20 mar the lavatory seat. The back rest 16 is also provided with a locking device which acts in connection with the U shaped seat brace 18. The back seat is provided with a recess 25, and a U shaped member 26 is inserted therein and fastened 25 to the back rest by means of the screws 27. A locking member 28, provided with a collar 29, is inserted through the U shaped member 26, and a spring 36 rests against the collar 29 and the top 30 of the U shaped member 26. The locking member 28 fits into a recess 30 in the U shaped seat brace 18, and thus holds the back rest in an angular position so that the sides will fit into the recesses 17 in the longitudinal arms 4. By means 35 of the cross arm 11 the longitudinal arms 4 are held in the said recesses 17.

The seat 2 is provided with two slots 35, which extend from the end of the seat inward, and these slots provide the means for receiving the 40 sides of the U shaped seat brace 18 when the back rest is collapsed inward and brought forward as shown in Figure 8. There is a small clearance 22 above the brace 18 so as not to interfere 45 with its operation.

One of the longitudinal arms 4 is provided with a ferruled hole at the rear end for the reception of one of the locking members of the cross arm 11 to provide means to prevent the cross arm 11 50 55

from being lost or broken when the lavatory seat is shipped or stored.

What I claim is:

1. In combination a collapsible lavatory seat, comprising a seat member, a back rest, a locking device attached to said back rest comprising a U shaped member, a locking member provided with a collar and mounted within said U shaped member, a spring encasing said locking member, and a brace adjustably connected to the seat member and pivotally supporting the said back rest, said locking member and adjustable brace cooperating
- 5
- 10

to hold the back rest in a locked and fixed position.

2. In combination a collapsible lavatory seat comprising a seat member; a back rest pivotally attached to the seat member, a locking device attached to said back rest comprising a U shaped member, a locking member provided with a collar and mounted within said U shaped member, and a spring encasing said locking member, said locking member and seat member cooperating to hold the back rest in a locked and fixed position. 5

JAMES H. BROWN.
